UNITED STATES PATENT OFFICE.

WILLIAM J. KNOX, OF DUBOIS, PENNSYLVANIA.

TANK-CAR.

1,151,324.

Specification of Letters Patent. Patented Sept. 21, 1915.

Application filed February 12, 1914. Serial No. 818,265.

To all whom it may concern:

Be it known that I, WILLIAM J. KNOX, a citizen of the United States, residing at Dubois, in the county of Clearfield and State of Pennsylvania, have invented certain new and useful Improvements in Tank-Cars, of which the following is a specification.

The invention relates to tank cars, and has for its primary objects, the provision of a construction in which the center of gravity of the tank is gotten at the lowest possible point relative to the rails; and the provision of a car of the character specified of simple, rigid construction with the draft and center sills in alignment to take care of and distribute the stress applied to the draft sill. Certain embodiments of the invention are illustrated in the accompanying drawings, wherein—

Fig. 1 is a partial plan view of the under framing of the car, Fig. 2 is a partial side elevation and partial section through one end of a car built in accordance with my invention, Fig. 3 is an end elevation of the car, Fig. 4 shows two partial half sections, the right hand half of the figure being taken on the line IV—IV of Fig. 2, and the left hand portion on the line IV'—IV' of Fig. 2, Fig. 5 is a plan view of a modified underframing construction, Fig. 6 is a partial longitudinal section through a car having the underframing of Fig. 5, Fig. 7 is a two-part view showing at the right hand portion an end elevation of the car, and at its left hand portion a section on the line VII—VII of Fig. 6, Fig. 8 is a section on the line VIII—VIII of Fig. 5, Fig. 9 is a plan view of a modified underframing construction, Fig. 10 is a longitudinal section through a car having underframing as in Fig. 9, and Fig. 11 is a two-part view, the right hand portion of the figure being a section taken on the line XI—XI of Fig. 10, the left hand portion being a section taken on the line XI'—XI' of Fig. 10.

In its preferred embodiment the car comprises a pair of trucks together with a tank having a full cylindrical central portion and end portions of substantially the same horizontal dimension as the central portion, but having their bottom sheets depressed in order to provide space for the trucks and that part of the underframing carried thereby. This arrangement gives a tank of the best type available, that is, substantially cylindrical throughout, and one which at

the same time may be placed with its center of gravity very close to the ground, since the recessed sheets at the ends of the tank provide a space for the trucks, thus permitting the bottom of the tank between the inner wheels of the truck to project down to a level approximating that of the axles of the wheels. This arrangement renders the use of a tank of relatively large diameter practicable, without making the car top-heavy. In its preferred form my invention contemplates the making of the re-curved sheets at the bottoms of the end portions of the tank integral with the draft sills and body sills, and the making of a portion of such sheets act as a segmental head for the center portion of the tank lying between the wheels, such object being accomplished by the use of a casting of appropriate form.

Referring first to the construction as illustrated in Figs. 1 to 4, 1 is the center portion of the tank, which as heretofore indicated is of full cylindrical cross section, while 2 is one of the end sections of the tank which would have the same cross section as the portion 1 if it were not for the use of the depressed bottom sheet 3. Bottom sheet 3 constitutes a portion of a casting, the inner end 4 of which (Fig. 2) constitutes a segmental head or closure for that portion of the tank having the full cylindrical cross section. As indicated in Fig. 2, the portion or sheet 4 is provided with a flange 5 to which the sheet 6 of the center portion 1 of the tank is riveted.

Also integral with the plate 3 is the transverse body bolster 7, such bolster being made of any approved contour and opposing the truck bolster 8 (Figs. 2 and 4). Also integral with the same casting of which the sheet 3 and body bolster 7 constitute a part, is the draft sill 9 which extends longitudinally of the car at its center, such draft sill being of the cross section indicated in Fig. 4. The edges of the sheet 3 are perforated as indicated in Figs. 1 and 4, and are secured by rivets to the parti-cylindrical shell of sheet metal, in the manner illustrated.

It will be understood that the construction at the other end of the car is the same as that above described, and that the right hand end of the center sill is connected to the underframe casting at such end of the car, in the same manner as that illustrated in Fig. 2. This center sill 10 may be constructed in any desired manner, and is ar-

ranged in alinement with the two draft sills 9, so that the two draft sills are mutually supported. In order to effectively secure the center sill 10 to the casting of which the 5 plates 3 and 4 form a part, such casting is provided with the projecting splice member 11 integral with the casting, such splice member lying inside the center sill 10 and being secured thereto by means of rivets.

10 It will be seen that the structure just described as illustrated in Figs. 1 to 4 is a most advantageous one. The construction permits of the retention of the cylindrical form, while at the same time permitting the 15 placing of the center line of the tank at a minimum distance from the ground. The tank can be made of larger diameter than has heretofore been possible, the only limitation being that the bottom plate 6 must be 20 at a sufficient distance above the road bed to avoid interference therefrom. It will be seen that this structure is possible by reason of the fact that the segmental head 4 is placed to the inside of the inner pair of 25 wheels 12, thus permitting the upper portion of the truck and wheels to fit up inside the space provided by using the re-curved or depressed sheet 3. The making of the re-curved plate 3, the body bolster, the draft 30 sill, the segmental head and the splice member 11, all in one integral casting is also an advantage because of the cheapness of the construction and because of its great rigidity. Other advantages of the construction 35 will be readily apparent to those skilled in the art.

Figs. 5, 6, 7, and 8 illustrate another modification in which the recessed portions at the ends of the tank are provided with sheet 40 metal closure plates 13 (Figs. 6 and 7), thus calling for a modification of the underframing as indicated in Fig. 5 wherein the cast plate 14 is made of the skeleton form illustrated instead of being a continuous plate 45 like the plate 3 in Fig. 1. The cast member 14 comprises a body bolster 15, a draft sill 16, a segmental head 17, and a splice member 18, substantially similar to the corresponding parts in the construction of Figs. 1 and 50 2. The center sill 19 is similar to the sill 10 of Figs. 1 and 2, being riveted to the splice member 18 in the same manner as in the construction of Figs. 1 and 2.

Figs. 9, 10, and 11 illustrate a modification of the invention in which a draft sill 20 built up of commercial sections, and a body bolster 21 also built up of commercial sections, are used instead of an integral casting as in the construction of Figs. 5 and 6. The 60 recessed sheet 22 is of sheet metal as in the construction of Figs. 5 and 6, thus differing from the construction of Figs. 1 and 2. The segmental head 23 is formed of a casting having integral therewith the splice members 24 and 25, the first of which is con-

nected to the draft sill 20 and the second of which is connected to the center sill 26. The general arrangement and other details of construction not above referred to, are substantially the same as in the cars of Figs. 1 70 and 2 and 5 and 6. Many other modifications might obviously be made without departing from the fundamental features of the invention as illustrated in the three types of construction heretofore described. 75

What I claim is:

1. In combination in a tank car, a pair of trucks at the ends of the car with draft sills and body bolsters, a tank comprising a shell cylindrical in cross section and of substantially uniform horizontal diameter from end to end, the lower portion of the shell at each end being set in to provide a space for the draft sills, body bolsters and trucks, and partial heads at the inner ends of the said 80 set in portions of the shell and on the inner sides of the inner wheels of the trucks, the central portion of the tank between the partial heads extending down below the said body bolsters and below the upper portions 85 of the wheels.

2. In combination in a tank car, a pair of trucks at the ends of the car with draft sills and body bolsters, a tank comprising a shell cylindrical in cross section and of substantially uniform diameter from end to end, the lower portion of the shell at each end being set recurved in to provide a space for the draft sills, body bolsters and trucks, partial 90 heads at the inner ends of the said set in portions of the shell and on the inner sides of the inner wheels of the trucks, and a center sill extending from one partial head to the other and lying inside the tank, the central portion of the tank between the partial heads extending down below the said body 95 bolsters and below the upper portions of the wheels. 100

3. In combination in a tank car, a pair of trucks at the ends of the car with draft sills and body bolsters, a tank comprising a shell cylindrical in cross section and of substantially uniform diameter from end to end, the lower portion of the shell at each end being set in to provide a space for the draft sills, body bolsters and trucks, partial heads at the inner ends of the said set in portions of the shell and on the inner sides of the inner wheels of the trucks, and a center sill 110 extending from one partial head to the other in alinement with the draft sills and lying inside the tank, the central portion of the tank between the partial heads extending down below the said body bolsters and below the upper portions of the wheels. 115

4. In combination in a tank car, a pair of trucks, body bolsters and draft sills carried thereby and a tank comprising a central cylindrical portion terminating short of the two trucks and extending down below the 120 125 130

5 tops of the wheels thereof and below the body bolsters and having partial heads at its lower ends adjacent the said wheels, and particylindrical end portions of the same diameter horizontally as the central portion but having pockets or recesses on their lower sides to receive the said trucks, body bolsters and draft sills.

5. In combination in a tank car, a pair of 10 trucks, body bolsters and draft sills carried thereby and a tank comprising a central cylindrical portion terminating short of the two trucks and extending down below the tops of the wheels thereof and below the 15 body bolsters and particylindrical end portions with the lower sides thereof cut away, plates provided with downwardly projecting ends closing the said cut out portions with the downwardly projecting ends constituting partial heads for the said central 20 portion of the tank, the said plates being formed so as to provide spaces for the reception of the body bolsters and draft sills.

6. In combination in a tank car, a pair of 25 trucks, a tank comprising a central portion terminating short of the inner wheels of the two trucks and extending down below the tops of such wheels, and end portions with the lower sides thereof recessed, a supporting member for each recessed side constituting a closure for the end of the said 30 central portion of the tank, a body bolster and a draft sill, and a center sill extending between the said members and lying in the 35 said central portion of the tank.

7. In combination in a tank car, a pair of trucks, a tank comprising a central portion terminating short of the inner wheels of the two trucks and extending down below the 40 tops of such wheels, and end portions with the lower sides thereof recessed, a supporting member for each recessed side constituting a closure for the end of the said central portion of the tank and a body bolster, a splice member on the inner side of the said 45 closure portion of each supporting member and a center sill secured at its ends to the said splice members and lying inside the tank.

8. In combination in a tank car, a pair of trucks, a cylindrical tank of substantially the same diameter from end to end and comprising a central portion terminating short of the inner wheels of the two trucks and

extending down below the tops of such 55 wheels, and end portions with the lower sides thereof cut away, and closure means for each of said cut away sides, such closure means comprising a closure plate for the open side of the end portion of the tank, 60 a closure plate for the end of the central portion of the tank, and a draft sill.

9. A tank car comprising a pair of trucks and body bolsters, a shell, the said shell having a full cylindrical center portion and 65 particylindrical end portions of substantially the same horizontal diameter as the central portion but provided with depressed bottom sheets to receive the trucks and body bolsters, the said sheets extending inwardly 70 past the inner wheels of the trucks, and the center portion of the tank projecting to a level below the tops of such wheels and below the body bolsters.

10. A tank car comprising a pair of 75 trucks and a shell, the said shell having a full cylindrical center portion and particylindrical end portions of substantially the same horizontal diameter as the central portion but provided with depressed bottom 80 sheets to receive the trucks, the said sheets extending inwardly past the inner wheels of the trucks, and the center portion of the tank projecting to a level approximately that of the axles of the wheels.

11. In combination in a tank car, a pair of trucks, a tank substantially cylindrical from end to end but having a section cut out of the lower side of each end to provide a pocket for the trucks, with the inner ends 90 of such pockets inside the inner wheels of the trucks, closure means for the cut out portions comprising bottom and end walls, framing including draft sills for supporting the car in said pockets, and a center sill extending from one of said end walls to the other, the central portion of the tank between the said end walls extending down a substantial distance below the tops of the 95 wheels.

In testimony whereof I have hereunto signed my name in the presence of the two 100 subscribed witnesses.

WM. J. KNOX.
